COFFEE TABLE

Arthur Luhrs, Miami, Fla.

Application June 1, 1953, Serial No. 25,273

Term of patent 14 years

(Cl. D33—14)

To all whom it may concern:

Be it known that I, Arthur Luhrs, a citizen of the United States, residing at Miami, in the county of Dade and State of Florida, have invented a new, original, and ornamental Design for a Coffee Table, of which the following is a specification, reference being had to the accompanying drawing, forming a part hereof.

I claim:

The ornamental design for a coffee table, substantially as shown.

ARTHUR LUHRS.
